UNITED STATES PATENT OFFICE.

FREDRICK ZIEMER, OF FREEPORT, NEW YORK.

TOOL-HANDLE FASTENER.

1,312,819.

Specification of Letters Patent.

Patented Aug. 12, 1919.

Application filed March 10, 1919. Serial No. 281,636.

To all whom it may concern:

Be it known that I, FREDRICK ZIEMER, a citizen of the United States, residing at Freeport, in the county of Nassau and State 5 of New York, have invented a new and useful Tool-Handle Fastener, of which the following is a specification.

This invention relates to a tool handle fastener, and has for its object to provide a 10 device of this kind which embodies novel features of construction whereby the head of a tool can be securely anchored upon the handle in such manner that it is not liable to become loose thereon, yet may be readily 15 removed therefrom for change or replacement. Other objects are to provide a tool handle fastener which is comparatively simple and inexpensively manufactured, which can be used with the conventional 20 types of tools without necessitating any marked changes in the construction thereof, which can be easily placed in position, and which will make it impossible for the tool head to become disengaged from the handle.

25 With the foregoing and other objects in view, which will appear as the description proceeds, the invention consists of certain novel details of construction and combination of parts which will be hereinafter more 30 fully described and pointed out in the claims it being understood that various changes may be made in the construction and arrangement of the parts without departing from the spirit, or sacrificing any of the advantages of the invention as set forth in the 35 appended claims.

Figure 1 is a sectional view of a hammer and handle as secured together by a fastener constructed in accordance with this invention.

40 Fig. 2 is a view similar to Fig. 1, taken at right angles to the showing in Fig. 1.

Figs. 3 and 4 are perspective views respectively of the anchoring member and the cap 45 plate.

Fig. 5 is a view in elevation parts being in section of a modified application of the invention.

Fig. 6 is a perspective view of a modified 50 form of anchoring member.

Referring to the drawing in which like reference characters refer to like parts throughout the several views, the numeral 1 designates a hammer handle provided with 55 a shoulder 2 which limits the extent to which the handle enters the eye of the tool, in this

instance a hammer 3 is shown. A transverse opening 4 is formed in the handle below the shoulder 2 and a transverse slot 5 of less width than the diameter of the hole 4 is cut from the end of the handle to the hole 4.

Before assembling the tool head and handle an anchoring member 6 is fitted to the hole 4 and slot 5; said member is made 60 of relatively light flexible material, preferably stamped from a single metal sheet and formed to approximately T shape, having a tubular portion 7 fitting the hole 4 and a pair of parallel strips 8 extending from 70 said tubular portion through the slot 5 and protruding from the end of the handle. A cap plate 9 having a projecting tongue or wedge 10, has holes 11 formed through the plate on either side of the wedge 10 and 75 slots 12 are cut in one face of the plate and terminate at one end in the holes 11. The cap plate is fitted to the end of the handle and overlapping the tool head, the wedge 10 enters between the strips 8, the ends of said 80 strips pass through the holes 11 and are then bent in opposite directions to seat in the slots 12, being practically flush with the top surface of the cap plate.

The cap plate serves not only to force the 85 handle into engagement with the tool head but with the member 6 to form a secure anchoring means.

A pin 13 is fitted to the tubular portion 7 to strengthen and prevent collapse of the 90 relatively thin metal tube. The ends of the pin may be upset as shown to prevent displacement of the same. It is obvious that if desired the tubular portion of the anchoring member may be disposed at a point more 95 remote from the end of the handle than is shown in the present instance.

In Fig. 5, is shown an application of the anchoring means for securing an ax 14 to the handle 15 thereof. A plurality of anchoring members 6 are fitted to the handle and the tongues or strips 8 pass through holes 16 in a cap plate 17 and are bent to seat in a slot 18 formed in the top surface of the cap plate.

105 The cap plate 17 is provided with a plurality of wedge members 19, which are forced into the end of the handle, thus forming an efficient locking means for large tools. This locking device is so constructed that it may 110 be easily removed from the handle and used again in case of damage to the tool or handle.

The preferred embodiment of the invention has been shown, described and claimed, but it is to be understood that changes may be made within the scope of the appended 5 claims without departing from or sacrificing any of the advantages of the invention.

In Fig. 6 is depicted an anchoring member 20 provided with a T head 21; this provides a flat surface 22 for contact with the 10 handle and has been found better adapted for use in some instances than the tubular form of anchoring member.

Having thus described my invention what is claimed is:

- 15 1. The combination with a handle having a transverse opening and a transverse slot extending to the opening from one end of the handle, and a tool head; of a head retaining plate at one end of the handle, an anchoring member insertible laterally into the slot and opening and having an enlarged end adaptable to be seated in the opening, the other end of said member detachably engaging the cap plate.
- 20 2. The combination with a handle having a transverse opening and a transverse slot extending to the opening from the end of the handle and a tool head adapted to be seated on the handle, of a head retaining plate, said plate having a longitudinal groove in one face and a wedge member projecting from the opposite face, an anchoring member insertible in the opening and slot in the handle, said member having an enlarged 25 end adapted to be seated in the opening, the other end of said member being detachably seated in the groove in the cap plate.
- 30 3. The combination with a handle having a transverse opening and a transverse slot extending to the opening from the end of the handle and a tool head adapted to be seated on the handle, of a head retaining plate provided with a longitudinal groove, openings formed in the plate communicating with the groove and intermediate the ends thereof, wedge shaped retaining 35
- 40 45

means projecting from the cap plate, anchoring means insertible in the slot and opening in the handle said anchoring means having an enlarged end adapted to be seated in the said opening, the other end of said member being seated in the slot and projecting through the openings in the cap plate, and bent to seat in the groove in the cap plate. 50

4. The combination with a handle having a transverse opening and a transverse slot of less width than the diameter of the hole, said slot extending to the opening from the end of the handle and a tool head adapted 55 to be seated on the handle, of a head retaining plate provided with a longitudinal groove, openings formed in the plate communicating with the groove and intermediate the ends thereof, wedge shaped retaining 60 means projecting from the cap plate, anchoring means insertible in the slot and opening in the handle, said anchoring member consisting of a tubular portion, a reinforcing member inclosed by the tubular portion and 65 tongues extending from the tubular portion and adapted to detachably engage the cap plate. 70

5. In a tool handle fastener the combination with a handle having a transverse opening therein and a slot extending from the end of the handle to said opening, a tool head provided with an opening receiving the handle and a cap plate applied to the end of the handle said cap plate having openings therethrough registering with the slots in the handle and an anchoring member seated in the transverse opening and slot, the free ends of the anchoring member extending through the opening in the cap plate and 85 bendable thereon. 75

In testimony that I claim the foregoing as my own, I have hereto affixed my signature in the presence of two witnesses.

FREDRICK ZIEMER.
